UNITED STATES PATENT OFFICE.

ALVIN C. WITTIG, OF MILWAUKEE, WISCONSIN.

CHECK DRAFT.

Application filed April 29, 1927. Serial No. 187,522.

This invention relates to improvements in check drafts, and more particularly to floating check drafts for furnaces and heaters.

It is one of the objects of the present invention to provide a floating check draft for mounting in a furnace or heater smoke pipe which is automatic in operation.

A further object of the invention is to provide a check draft of the class described which is automatically operated by the draft through the pipe thereby constantly regulating the check on the fire to correspond with the draft and changes in the draft, resulting in a saving in fuel and a uniform fire.

15 A further object of the invention is to provide a check draft which will not require any attention nor adjustments.

A further object of the invention is to provide a check draft of the class described which 20 may be releasably locked in closed position if it is desired to bring up the fire very quickly.

25 A further object of the invention is to provide a check draft of the class described which is of very simple construction and with which the smoke pipe of any heater may be very easily equipped.

30 A further object of the invention is to provide a floating check draft which is inexpensive to manufacture and install, is strong and durable, and is well adapted for the purpose set forth.

With the above and other objects in view the invention consists of the improved floating check draft and its parts and combinations as set forth in the claim, and all equivalents thereof.

35 In the accompanying drawing in which the same reference characters indicate the same parts in both of the views:

Fig. 1 is a vertical sectional view showing the improved floating check draft; and

Fig. 2 is a plan view of the same.

Referring now more particularly to the drawing it will appear that the numeral 5 indicates a cylindrical member which is hollow and has a bottom portion 6 and a top 7 provided with a circular opening 8 of a substantial size. The wall of said member 5 is provided with a pair of openings 9 from which extend opposed pipes 10, each of which are connected with pipe sections 11. The member 5 is adapted to be interposed in the smoke pipe of a furnace or heater and one of the pipe sections 11 connected thereto will 55 extend to the chimney and the other pipe section 11 will extend to the furnace.

A bracket or supporting member 12 is secured to the top 7 of the member 5 and spans the opening 8. A rod 13 is threaded through 60 the intermediate portion of the bracket and the lower portion of the rod is formed with an eyelet 13' to which is secured one end portion of an elongated coiled spring 14. The other end portion of the spring is attached to the 65 center of a valve plate 15. Said plate 15 is positioned within the cylindrical member 5 below the opening 8 in the top thereof and is of a diameter greater than the diameter of the opening 8. The plate is thin and very light, 70 being preferably formed of aluminum. The rod 13 may be adjusted with respect to the bracket and is held in adjusted position by means of a nut 16.

The undersurface of the top 7 of the member 5 is covered by a sheet 17 of insulating material as asbestos, said sheet, of course having a circular opening therein corresponding to the opening in the top 7.

In use, the cylindrical member is positioned 80 in the smoke pipe of a furnace or heater as described and the draft through the pipe will cause a suction which will draw down the plate 15 away from the opening 8, allowing air to enter through the opening thus exposed 85 to act as a check. The downward movement of the plate will be against the tension of the spring 14 which should be adjusted so as to normally hold the plate tightly against the insulating sheet 17, and of course if there is no 90 draft through the pipe the plate will remain in closed position and the amount which the plate will draw away from the opening depends entirely on the strength of the draft. Hence, if there is a strong draft the opening 95 will be greatly exposed to give a strong counter-acting check, whereas if the draft is weak the opening will be only slightly exposed and in this manner the needed draft on the fire is automatically regulated. It has 100 been found in practice that the plate will constantly bob up and down slightly because of the fluctuations in the draft. The sheet 17 serves not only as an insulating medium but deadens the sound and prevents a metallic 105 ring caused by contact between the plate and the top.

It is sometimes desirable that the plate be

held in closed position to prevent a check as for instance when a fire is being built or a quick fire is desired. For that purpose a rod 18 is pivotally mounted through a side portion of the wall of the member 5 in proximity to the top thereof and the rod is held against withdrawal by cotter pins 19. If the outer end portion of the rod is pulled downwardly, as shown in dotted lines in Fig. 1 the inner 10 end portion of the rod will be raised and will engage the mid-portion of the plate 15 to hold the same firmly in closed position. The outer end portion of the rod 18 has depending therefrom a chain 20 which has at its lower 15 end portion a hook 21 which may be engaged with the lower rim portion of the member 5 to releasably hold the rod in plate engaging position.

From the foregoing description it will be seen that the improved floating check draft is

of very simple and novel construction, and is well adapted for the purpose described.

What I claim as my invention is:

The combination with a heater smoke pipe, of a hollow member interposed therein, said hollow member having an opening therein, a bracket attached to said hollow member and spanning the opening, an adjustable normally contracted spring member suspended from the mid portion of said bracket, a thin plate 25 centrally attached to said spring member and positioned within the hollow member to normally control the opening therein, a pivotal rod locking member extending adjacent said plate for releasably holding the same in a 30 closing position with respect to the opening, and means for locking said rod in a plate engaging position.

In testimony whereof, I affix my signature.

ALVIN C. WITTIG.
